(No Model.)

G. HATTON.

CONVERTER FOR THE MANUFACTURE OF IRON AND STEEL.

No. 308,963.

Patented Dec. 9, 1884.

UNITED STATES PATENT OFFICE.

GEORGE HATTON, OF HAGLEY, COUNTY OF WORCESTER, ENGLAND.

CONVERTER FOR THE MANUFACTURE OF IRON AND STEEL.

SPECIFICATION forming part of Letters Patent No. 308,963, dated December 9, 1884.

Application filed September 15, 1884. (No model.) Patented in England June 27, 1884, No. 9,500.

To all whom it may concern:

Be it known that I, GEORGE HATTON, a subject of the Queen of Great Britain, residing at Hagley, in the county of Worcester, England, have invented certain new and useful Improvements in Converters Employed in the Manufacture of Iron and Steel, (for which I have applied for Letters Patent in Great Britain, my application bearing date the 27th day 10 of June, 1884, and being numbered 9,500, but have not yet obtained the grant of such Letters Patent,) of which the following is a specification.

In converters employed in the manufacture 15 of iron and steel as usually constructed and arranged, considerable injury is frequently done to the blast boxes and valves through which blast is supplied to the tuyeres on account of the leakage of the metal through the converter-lining; and the object of this invention is to provide against such injury, and also to simplify the lower part of the converter, (that is, the part containing the tuyeres and the part of the lining liable to be most 20 readily burned out,) which is in this case removable, by omitting from such lower part the usual blast chamber or boxes. I attain this object by making the lower part of the converter, containing the tuyeres and that part of 25 the lining which is liable to be most rapidly burned out, removable from the upper part of the converter, substantially as has been sometimes heretofore adopted; but the blast receiver or boxes, with any necessary blast- 30 valves, are carried around the upper part of the converter, so as to dispense entirely with a blast chamber or boxes around the lower part thereof, and the blast is conveyed therefrom by means of a separate supply-pipe to 35 each tuyere. These supply-pipes are constructed so that they may be easily disconnected at any convenient point in their length, in order that the lower part of the converter may be readily removed for replacement with a duplicate.

My invention will be clearly understood by reference to the accompanying drawing, which is a half vertical section and a half elevation of a fixed converter carried by columns, so as 45 to admit of the ready removal and replacement of the bottom.

A A are the columns supporting the upper part, B B, of the converter. The lower part, C, of the converter is held by means of a flange or angle ring, D, and bolts therethrough to a flange or angle ring, E, at the bottom of the upper part of the converter, so that the lower part, C, may be readily removed from the upper part and replaced with a duplicate. The lower part, C, contains the 55 tuyeres, of ganister or other refractory material, one of which is shown in section at F, and also that part of the furnace-lining which is liable to be most quickly burned out.

G G are air chambers or boxes carried with 60 the upper part of the converter, and therefore remaining fixed, while the lower part is removed for relining.

H is a plain baffle-valve for regulating the passage of blast to a tuyere, and J J, &c., 65 are blast-pipes. A separate pipe, J, passes down from each blast chamber or box G to each of the tuyeres. Each pipe J forms a ball-and-socket or universal joint with the short pipe K, containing the valve, and this 70 joint is tightened up by means of a bridle or strap, L, and set-screw M thereunder, as shown. Each pipe J is connected, also, by means of a flange-joint, N, with a mounting, O, on the casing of the lower part, C, of the 75 converter. The holes a a through the flanges at a joint, N, are elongated in vertical direction, and are open to the edges of the flanges, as shown, so as to allow, respectively, for one of the flanges not being exactly vertically opposite to the other, and to facilitate the removal of the bolts. K is the usual tapping-hole.

When it is desired to remove the lower part, C, of the converter, each flange-joint N 80 is disconnected, and each set-screw M at the bottom of a bridle, L, is slackened, and the pipes lettered J are then pulled back at their lower ends to be as clear from the mounting O as may be desired, and are held in such position by tightening up the set-screws M. When a converter-bottom, C, has been removed and replaced, the pipes J are of course 85 again connected up.

b b are sight and cleaning holes for the 90 tuyeres. The joint between the upper and lower parts of the converter is made perfectly

sound by ramming ganister in around the annular wedge-shaped space *c*, formed between the bottom of the upper lining and the top of the lower lining.

5 P P are rails upon which a trolley is run for bringing in and removing converter-bottoms, and such trolley may, if desired, be raised and lowered by means of a hydraulic ram or any convenient means, to facilitate 10 fixing and unfixing the bottoms. The columns A A are shown broken in their length for convenience of illustration. Sufficient room is allowed, preferably below the converter, to admit of the bottom being lowered 15 clear of all obstructions to its removal. It will now be seen that the blast chambers or boxes remain in position upon the removal of the lower part of the converter, and that, if during the working of the converter any 20 metal escapes through the lining of the lower part thereof, such metal cannot find access to the blast chambers or boxes or to the valves immediately thereunder. The removable bottom is also much simpler and less expensive 25 than when an air chamber or boxes are attached thereto.

My invention has been described and illustrated specially with reference to a fixed converter; but it will be readily understood to be 30 applicable also in the case of a Bessemer or tipping converter, in which (as is sometimes

done) the tuyeres are arranged in the side of the converter for the purpose of blowing with a low-pressure blast, instead of in the bottom, as is usual when a high-pressure blast is employed. 35

Having thus stated the nature of my said invention and particularly described the manner of performing the same, I declare that what I claim is— 40

1. In a converter employed in the manufacture of iron and steel, the combination, with the removable bottom of the converter, containing the tuyeres, of the upper part of the converter, carrying the blast-chamber, and 45 means, substantially as described, for carrying the blast from the blast-chamber to the tuyeres, substantially as and for the purposes set forth.

2. In a converter employed in the manufacture of iron and steel, the combination of the blast-boxes G with the blast-pipes J and the removable bottom C, all constructed and arranged substantially as and for the purpose herein described and shown. 50

In witness whereof I have hereunto signed my name in the presence of two subscribing witnesses.

GEORGE HATTON.
